CHAUNCY GRAHAM, OF ELIZABETH, NEW JERSEY.

Design No. 4,843, dated April 25, 1871.

DESIGN FOR A COTTAGE FRONT.

The Schedule referred to in these Letters Patent and making part of the same.

To all whom it may concern:

Be it known that I, CHAUNCY GRAHAM, of Elizabeth, in the county of Union and State of New Jersey, have invented a new and improved Design for Cottage Front; and I do hereby declare the following to be a full, clear, and exact description thereof, which will enable those skilled in the art to make and use the same, reference being had to the accompanying drawing forming part of this specification, which drawing represents a front elevation of a cottage ornamented according to this invention.

The principal features of this design are two arcs on the sides of the attic window, and a roof-shaped cornice connected to said arcs by two upright members and surmounting the attic window, while the edges of the French roof are concave.

In the drawing—

The letter A designates the front of a cottage,

which is provided with a French roof, B, and an attic window, C.

From the main cornice D of the cottage extend two arcs, E, one on each side of the attic window C, and from the upper end of these arcs rise two straight members, F, which support the roof-shaped cornice G surmounting the attic window C.

The edges H of the roof are concave, as shown.

By the arcs E and the roof-shaped cornice G a new and ornamental appearance is given to the front of the cottage.

What I claim as new, and desire to secure by Letters Patent, is—

The design for a cottage front, as herein shown and described.
